UNITED STATES PATENT OFFICE.

ADELORD BOURGEOIS, OF SWAMPSOFT, MASSACHUSETTS, ASSIGNOR TO UNITED SHOE MACHINERY CORPORATION, OF PATERSON, NEW JERSEY, A CORPORATION OF NEW JERSEY.

MACHINE FOR MOUNTING SHOES ON LASTS.

1,360,084.

Specification of Letters Patent. Patented Nov. 23, 1920.

Application filed May 21, 1918. Serial No. 235,865.

To all whom it may concern:

Be it known that I, ADELORD BOURGEOIS, a citizen of the United States, residing at Swampscott, in the county of Essex and State of Massachusetts, have invented certain Improvements in Machines for Mounting Shoes on Lasts, of which the following description, in connection with the accompanying drawings, is a specification, like 10 reference characters on the drawings indicating like parts in the several figures.

This invention relates to machines for use in the manufacture of boots and shoes for mounting shoes on lasts. Such machines are 15 of particular utility in the manufacture of turn shoes for mounting the shoe on the second last after the shoe has been turned, but it will be evident from a consideration of the construction and manner of operation of the machine herein shown that the 20 invention is not limited in utility to the manufacture of shoes of this particular type.

An object of the invention is to provide a machine of improved construction by the 25 use of which a shoe may be mounted on a last in an expeditious and effective manner with comparatively little effort upon the part of the operator and without injury either to the shoe or to the last. An important 30 feature of the invention consists in novel means for working a shoe over a last by engagement with the shoe. The construction illustrated as an embodiment of this feature comprises a band for embracing the heel end portion of the shoe and means for closing 35 the band upon the shoe and for operating it to work the heel end portion of the shoe smoothly over the last. The construction shown comprises also novel mechanism for 40 operating the shoe engaging means, whereby the operator, by movement of his foot, is enabled to move the shoe engaging means into or out of engagement with the shoe at will and also to impart to said means movements 45 for working the shoe over the last.

A further feature of the invention comprises a novel construction and arrangement of means for forcing a last into a shoe in combination with means for working the 50 shoe over the last. Still other features are to be recognized in novel means for forcing a last into a shoe, novel means for guiding the last in its movement into the shoe, novel means for positioning the shoe and for sup-

porting it against the pressure of the last, 55 and in various details of construction and combinations of parts, all of which will now be described with reference to the accompanying drawings and pointed out in the claims.

In the drawings,

Figure 1 is a perspective view of a machine in which the invention is embodied with portions broken away to illustrate the interior construction;

Fig. 2 is a view in side elevation, and partially in vertical section, of a portion of the machine shown in Fig. 1; and

Fig. 3 is a view similar to Fig. 2 of a portion of the machine, illustrating the positions of the parts at a different stage in the operation of the machine.

The machine herein shown comprises a column 2 adapted to stand upon the floor, the column having at its upper end a horizontal table 4 upon which is secured a plate 6 to provide a support for the forepart of a shoe into which a last is to be inserted. Upon the plate 6 there may be positioned a sheet of comparatively yieldable material 8 such as leather or rubber to prevent injury to the surface of the sole during the operation of forcing the last into the shoe. Secured to the column 2 is a bracket 10 which supports a plate 12 the upper surface 85 of which is hollowed out to adapt the plate to serve as a mold (see Fig. 2) for shaping the heel seat portion of the sole as the last is forced into the shoe. The bracket 10 is provided with a vertical slot 14 which in cooperation with a securing bolt 16 permits the bracket and the plate 12 to be adjusted vertically. The bracket is preferably positioned, as shown, to support the heel end portion of the shoe at a higher elevation 90 than the forepart, the rear portion of the shoe being thus lifted relatively to the forepart to substantially the same extent as it is in the completed shoe by the action of the attached heel. By positioning the shoe in this manner with its sole inclined downwardly toward the toe end, the operation of forcing the last into the shoe in the manner hereinafter explained is greatly facilitated.

Mounted for movement vertically in a bearing 18 on a bracket 20 secured to or formed integrally with the column 2 is a rod 22 upon the upper end of which is

mounted an arm 24 which carries a last engaging spindle 26. The diameter of the spindle 26 is greater than the normal diameter of the usual socket or spindle hole *a* in the heel end portion of a last, and at its lower end the spindle is rounded in substantially semi-spherical form to permit it to seat within the upper end of the socket *a* and thus to maintain an engagement with the last in a definite location while permitting the last to tip relatively to the spindle during its movement into the shoe. The spindle 26 has threaded engagement with the arm 24 to permit it to be adjusted vertically in conformity to different conditions encountered in operating upon shoes of different sizes and styles. In order to permit the spindle 26 to be readily positioned in accordance with the location of the hole *a* in the last irrespective of the length of the shoe and the last or of variations in the position of the spindle hole in different lasts, and also to permit the spindle to remain in engagement with the last in the same location continually during the movement of the last into the shoe, provision is afforded for movement of the spindle relatively to the rod 22 in directions lengthwise of the shoe. In the construction shown the arm 24 is swiveled upon the upper end of the rod 22, the arm carrying a set screw 28 which engages in an annular groove 30 in the rod to afford an operative connection between the rod and the arm while permitting the arm to swing laterally.

For the purpose of imparting operating movement to the rod 22 to force the spindle 26 downwardly, the rod is connected at its lower end to a treadle lever 32 pivotally mounted at 34 upon the column 2. A spring 36 serves normally to maintain the lever 32 and the spindle 26 in an elevated position. Secured to the column 2 adjacent to one side of the treadle lever is a ratchet plate 38 the teeth of which are pointed downwardly and are arranged to engage a plate 40 secured to the lever 32 to lock the lever and its connected parts against upward movement in response to the tension of the spring 36. Provision is afforded for a slight lateral play of the lever 32 to permit the operator to effect engagement or disengagement of the plate 40 with the teeth of the plate 38. By means of this construction the lever 32 may be located in such manner as to hold the spindle 26 against upward retractive movement after the parts have been operated to force the last either partially or entirely into the shoe, as will be hereinafter more fully explained.

In order to assist in positioning the shoe for the operation of the machine, and also to insure against forward movement of the shoe, the machine is provided with a laterally curved shoe positioning member 42

which is supported upon a bracket 44 on the table 4 in position to project in front of the toe end of the shoe. The member 42 is connected to the bracket 44 by means of a hinge 46 which permits the member to rock laterally and thus to conform readily to the location of the toe end of the shoe, whether the shoe be a right or a left. The bracket 44 is secured to the table 4 by means of a bolt 48, this bolt extending through a slot 50 in the bracket which permits the shoe positioning member 42 to be adjusted in directions lengthwise of the shoe, in order to adapt the machine to operate upon shoes of different sizes. In addition to the member 42, the machine is also provided with shoe positioning members 52 which are arranged to engage the shoe at the opposite sides of the forepart, these members being supported for rocking movement upon brackets 54 in substantially the same manner in which the member 42 is supported upon the bracket 44. The brackets 54 are secured adjustably to the table 4 in substantially the same manner as the bracket 44 and permit the members 52 to be spaced different distances apart for shoes of different widths. The members 42 and 52 are preferably faced with yieldable material 56 such for example as leather or rubber in order to insure against injury to the surface finish of the shoe.

In order to assist in guiding the last into the shoe during the downward movement of the spindle 26 effected in the manner hereinbefore explained, the machine is provided with a member 58, herein termed a shoe horn, which is preferably formed of metal or of similar resistant material having a smooth surface along which the rear end portion of the last may slide as it is forced into the shoe, this member being curved laterally in approximate conformity to the lateral curve of a last and a shoe around the heel end portion. In order to position the member 58 for convenient use and to permit it to be readily withdrawn from the shoe when required, it is connected by means of a flexible strap 60 to an arm 62 carried by a pivot rod 64 which is mounted to turn in a lug on the arm 24 and is provided at its opposite end from the arm 62 with a second arm 66 adapted to serve as a handle. By swinging the arm 66 the arm 62 may thus be operated to pull the horn 58 out of the shoe whenever the operator so desires.

Positioned at the rear of the heel end portion of the shoe, as located upon the supporting plate 12, is an end embracing band comprising a portion 68 which may be formed of rubber or other flexible material adapted to be wrapped about the heel end portion of the shoe in frictional engagement with the upper, the rubber strip 68 in the construction shown being secured to a curved strip 130

70 of spring metal provided near its opposite end portions with projecting pins 72. The heel band, comprising the rubber strip 68 and the metal piece 70, is supported at its 5 rear end upon an equalizing bar 74 upon the opposite ends of which are pivoted arms 76 provided with slots 78 through which the pins 72 extend, the arms 76 thus serving to support the forwardly projecting wings 10 of the heel band. Connected to lateral extensions of the respective arms 76 are two divergently projecting arms 80 of a holder 82 which is mounted to slide up and down upon a bar 84 secured by means of set screws 15 86 to a lever 88 which is pivoted at 90 upon a bracket 92 on the column 2. At its rear end the lever 88 is connected by means of a link rod 94 to a treadle lever 96 pivoted on a stud 98 on the column 2. In the use of this 20 construction movement is imparted to the lever 88 through downward movement of the treadle lever 96 to swing the bar 84 and the holder 82 in a direction to carry the heel band 68 into engagement with the shoe. 25 The wings of the heel band are maintained normally apart by the action of the spring plate 70 in such manner as to cause the band to engage the shoe first at its rear end face when it is swung toward the shoe in the 30 manner above described. After such engagement with the shoe has been effected, pressure of the arms 80 on the holder 82 against the lateral projections of the two arms 76 causes these two arms to swing about their pivotal connections with the bar 74 and thus to press the wing portions of the heel band against the sides of the shoe, the band thus being finally wrapped about the heel end portion of the shoe in frictional 35 engagement with the upper material.

Projecting from the rear of the holder 82 is an arm 100 which is connected by means of a link 102 to one arm 104 of a bell crank lever which is pivoted at 106 upon the treadle lever 96, the other arm 108 of the bell crank being connected by means of a link 110 to an ear 112 formed on a foot rest member 114 which is pivoted on a rod 116 at the front end of the lever 96. It will be evident 45 that with this construction rearward rocking movement of the member 114 about its pivot 116 will serve through the connections comprising the link 110, the bell crank 108, 104 and the link 102 to impart upward sliding movement to the holder 82 upon its supporting bar 84 and thus to move the heel band 68 upwardly in frictional engagement 50 with the heel end portion of the shoe. In addition to the function of operating the heel 55 band in this manner, the member 114 also serves as means for imparting pressure of the operator's foot to the treadle lever 96 to swing the heel band toward the shoe and hold it in engagement with the shoe in the 60 manner hereinbefore explained.

The connection between the link 94 and the arm 88 comprises a slot 118 in the arm 88 through which a bolt 120 (Fig. 2) carried by the link 94 extends, this connection affording provision for adjustment to vary 70 the effective leverage under which pressure against the shoe is imparted to the heel band. The heel band may be adjusted to different heights in conformity to different altitudes of the shoe supporting bracket 10 by loosening 75 the set screws 86 and sliding the bar 84 to different positions on its supporting lever 88.

In the use of the machine constructed as hereinbefore described, a shoe in which a 80 last has been partially inserted by hand is positioned upon the shoe support substantially as indicated in the drawings. The operator then positions the guide member or horn 58, which is supported by the arm 62 85 continuously in convenient location for use, within the heel end portion of the shoe between the shoe and the last, substantially as indicated in Fig. 2. By downward pressure upon the treadle 32, the spindle 26 is then moved into engagement with the top of the neck portion of the last, the arm 24 being swung by the operator as required to cause the rounded end of the spindle to be seated at the upper end of the spindle hole a. 90 Through continued depression of the treadle 32 the spindle 26 is caused to force the last downwardly and forwardly into the shoe while the horn 58 serves as a guide to assist in imparting forward movement to the last 100 and also to prevent the upper of the shoe at the heel portion from being forced downwardly with the last in such manner as to form wrinkles. The operator may continue to depress the treadle 32 until the last has 105 been entirely forced into the shoe, or if desired, may stop the operation before the movement of the last into the shoe has been entirely completed. During the downward movement of the last into the shoe the handle 66 may, if the operator so desires, be manipulated to withdraw the horn 58 partially from the shoe and thus facilitate the 110 relasting operation through tendency of the horn in its withdrawing movement to pull the upper materials upwardly over the last. If desired, however, any withdrawal of the horn from the shoe may be postponed until downward movement of the spindle 26 has 115 been completed. The operator may then, by 120 manipulation of the handle 66, withdraw the horn from the shoe and position it entirely out of the way of subsequent operations upon the shoe.

After the treadle 32 has been moved downward to force the last into the shoe fully or partially as hereinbefore explained, the operator, by a slight lateral movement of the treadle lever, will cause the plate 40 to engage one of the teeth on the plate 38 130

and thus lock the lever and its connected parts against retractive upward movement. In order to complete the relasting operation with respect to the rear end portion of the 5 shoe and cause the upper to be drawn smoothly and free from wrinkles over the heel end portion of the last, the operator will then place his foot upon the rest 114 and by a direct downward pressure, without 10 rocking the member 114, depress the treadle lever 96 to swing the heel band toward the shoe and wrap it about the heel end portion of the shoe in the manner hereinbefore explained. While maintaining the 15 pressure upon the treadle to hold the heel band tightly about the shoe, the operator will then rock the member 114 rearwardly about its pivot 116 and thereby impart an upward movement to the heel band in frictional engagement with the upper materials 20 to pull or draw the upper tightly over the last while the last is restrained from upward movement by its engagement with the spindle 26. If desired, the operator may 25 repeat this operation of the band upon the shoe, causing it to release and then to re-engage the shoe and wipe the upper upwardly as many times as he desires. This operation of the heel band upon the shoe 30 may be performed if desired before the last has been entirely forced into the shoe by the action of the spindle 26. In case it is noted, for example, during the operation of forcing the last into the shoe that there 35 is a tendency for the upper at the rear portion of the shoe to be wrinkled, the treadle lever 32 may be located in an intermediate position and the heel band then operated in the manner hereinbefore explained to work 40 the upper over the last. Subsequently the treadle 32 may be further depressed to complete the operation of forcing the last downward into the shoe, after which if desired the heel band may be again operated to 45 draw the upper finally in a smooth and un- wrinkled condition over the last. It will be evident that the shoe horn 58 may or may not be withdrawn prior to the operation of the heel band or may be manipulated simultaneously 50 with the band to work the shoe over the last.

During the final stage of the depressing movement of the spindle 26, whereby the last is forced downward with firm pressure upon the sole at the heel end portion, the mold 55 12 becomes effective to shape the heel seat portion of the sole substantially as desired for the subsequent attachment of the heel, and thus, in a measure at least, to eliminate 60 the necessity for any subsequent shaping action upon this portion of the sole.

While the heel band and its operating mechanism for use in drawing the heel end portion of a shoe smoothly and free from

wrinkles over a last are herein shown as 65 part of a machine for use in mounting shoes on lasts, it will be evident that this portion of the structure involves features of utility irrespective of the particular character of other attendant mechanism or of 70 other operations which a machine including such structure may be adapted to perform, and the drawings and description are therefore to be regarded as merely illustrative and not as implying a limitation with respect to the scope of the invention.

Having described the invention, what I claim as new and desire to secure by Letters Patent of the United States is:

1. A machine of the class described having, in combination, means for forcing a last into a shoe, means constructed and arranged to be closed about the heel end portion of the shoe in frictional engagement with the upper along the opposite sides of the heel 85 portion, and mechanism for operating said upper engaging means to draw the shoe over the last against the resistance of said forcing means.

2. A machine of the class described having, in combination, means for forcing a last into a shoe, a flexible end embracing band, and means for closing said band about the heel end portion of the shoe and moving it toward the top of the last to work the 95 heel end portion of the shoe over the last.

3. A machine of the class described having, in combination, means for forcing a last into a shoe, mechanism for locking said forcing means against retractive movement, 100 and means for engaging the shoe frictionally along the opposite sides of the heel portion and drawing it over the last against the resistance of said forcing means.

4. A machine of the class described having, in combination, means for forcing a last into a shoe, mechanism for locking said forcing means against retractive movement, a flexible end embracing band, and means for closing said band about the heel end 110 portion of the shoe and moving it toward the top of the last against the resistance of said forcing means to work the heel end portion of the shoe over the last.

5. A machine of the class described having, in combination, means for engaging a last partially inserted in a shoe, treadle means for operating said last engaging means to force the last into the shoe, and treadle operated means constructed and arranged for use subsequently to engage the upper of the shoe frictionally and draw it over the last.

6. A machine of the class described having, in combination, means for forcing a last into a shoe, an end embracing band, and treadle operated means for first closing said band about the heel end portion

of the shoe and then moving the band toward the top of the last to work the shoe over the last.

7. A machine of the class described having, in combination, means for forcing a last into a shoe, and means constructed and arranged to be moved subsequently into engagement with the exterior surface of the heel end portion of the upper of the shoe 10 and operated to draw the shoe over the last against the resistance of said forcing means.

8. A machine of the class described having, in combination, means for forcing a last into a shoe, means for gripping the heel end portion of the shoe at opposite sides, and mechanism for bringing said gripping means into frictional engagement with the shoe and drawing the shoe over the last against the resistance of said forcing means.

9. A machine of the class described having, in combination, means for forcing a last into a shoe, means for gripping the heel end portion of the shoe at opposite sides, 25 and means for enabling the operator repeatedly to close said gripping means on the shoe and move said means in a direction to work the shoe over the last.

10. A machine of the class described having, in combination, means for engaging a last partially inserted in a shoe, means for gripping the heel end portion of the shoe, and means for enabling the operator to impart last and shoe forcing movements alternately to said last engaging means and gripping means to cause the shoe to be mounted on the last.

11. A machine of the class described having, in combination, means for forcing a last into a shoe, means for gripping the heel end portion of the upper of the shoe, and means for enabling the operator to lock said forcing means against retraction at an intermediate stage in its operative movement and 45 then to operate said gripping means in frictional engagement with the shoe to work the shoe over the last.

12. A machine of the class described having, in combination, means for engaging a last partially inserted in a shoe, mechanism for operating said last engaging means to force the last into the shoe, and means comprising a flexible end embracing band constructed and arranged to engage the 55 upper of the shoe frictionally along the opposite sides of the heel portion and through relative movement of said upper engaging means and the last to work the shoe over the last.

60 13. A machine of the class described having, in combination, means for forcing a last into a shoe, means comprising a flexible band constructed and arranged to engage the upper of the shoe frictionally along the

opposite sides of the heel portion to cause 65 the heel end portion of the shoe to be mounted smoothly on the last through relative movement of the last and said band, and means for enabling the operator to close said band on the shoe or to release it therefrom at will.

14. In a machine of the class described, the combination with means for engaging a last in a shoe, of a flexible end embracing band, connections to the opposite end portions of said band, and means for operating said connections first to wrap the band about the heel end portion of the shoe and then to move the band toward the top of the last to work the shoe over the last against the resistance of said last engaging means.

15. In a machine of the class described, the combination with shoe positioning means and means for engaging a last in a shoe positioned by said means, of means for frictionally engaging the upper of the shoe, a support movable to carry said upper engaging means into shoe engaging position, and mechanism for moving said upper engaging means relatively to said support to 90 work the shoe over the last against the resistance of said last engaging means.

16. In a machine of the class described, the combination with means for engaging a last in a shoe, of means for frictionally engaging the upper of the shoe, a support mounted for swinging movement to carry said upper engaging means into shoe engaging position, and mechanism for moving said upper engaging means toward the 100 top of the last while said means is in engagement with the shoe to work the shoe over the last.

17. In a machine of the class described, the combination with means for engaging a last in a shoe, of means for frictionally engaging the upper at the heel end portion of the shoe, an operating member arranged to be engaged by the operator's foot, and connections between said member and the 110 upper engaging means to cause said means to be moved into engagement of the shoe by a movement of said member in one direction and to be operated to work the shoe over the last by a different movement of 115 said member.

18. In a machine of the class described, the combination with means for engaging a last in a shoe, of a heel embracing band, a foot rest, and connections between said band and foot rest to cause the band to be closed about the heel end portion of the shoe by a downward movement of said foot rest and to be operated to work the upper of the shoe over the last by a swinging movement of said 120 foot rest while the band is held in engagement with the shoe.

19. In a machine of the class described,

- the combination with means for engaging a last in a shoe, of a heel embracing band, a holder upon which said band is mounted, a support for said holder mounted for swinging movement to carry the band into or out of engagement with the shoe, a treadle lever connected to said support for operating it, a foot rest pivotally mounted on said treadle lever, and connections between said foot rest and holder to cause a swinging movement of the foot rest to operate the band for working the shoe over the last while the band is held in engagement with the shoe by the depression of said foot rest and lever.
20. In a machine of the class described, the combination with means for engaging a last in a shoe, of a flexible heel embracing band, a holder for said band comprising lever arms upon which the end portions of the band are supported, means for causing said arms to swing the end portions of the band into shoe engaging position, and means for operating said holder to cause the band to work the shoe over the last while the band is held in engagement with the shoe.
25. In a machine of the class described, the combination with a support for the bottom of a shoe and means for engaging the top of a last in a shoe on said support, of means for engaging the rear end portion of the upper of the shoe frictionally and drawing it over the last against the resistance of said last engaging means.
30. In a machine of the class described, the combination with means for forcing a last into a shoe, of shoe supporting means arranged to engage the bottom of the shoe and comprising relatively adjustable forepart and heel-seat supporting portions, and means for maintaining the adjusted relation of said different portions of the supporting means.
35. In a machine of the class described, the combination with means for forcing a last into a shoe, of a support for the forepart of the shoe, and an additional support for the heel end portion of the shoe arranged to maintain the heel end portion of the shoe at a higher elevation than the forepart and adjustable to vary said elevation.
40. In a machine of the class described, the combination with means for forcing a last into a shoe, of a support for the bottom of the forepart of the shoe, an additional support for the heel seat portion of the shoe, said supports being relatively adjustable to vary the distance between the planes of their shoe supporting surfaces, and means for maintaining the adjusted relation of said supports.
45. In a machine of the class described, the combination with means for forcing a last into a shoe, of a support for the bottom of the shoe, and an abutment arranged to project laterally of the shoe across the toe end, said abutment being mounted for movement in response to engagement with the shoe into adjusted relation to the contour of the shoe.
50. In a machine of the class described, the combination with means for forcing a last into a shoe, of a support for the bottom of the shoe, an abutment arranged to project across the toe end of the shoe, and other abutments arranged to extend along the opposite sides of the forepart of the shoe, said abutments being adjustable for shoes of different sizes and also movable in response to engagement with the shoe to cause them to be positioned in accordance with the contour of the shoe.
55. In a machine of the class described, the combination with means for supporting a shoe, of means for forcing a last into the shoe comprising a spindle of greater diameter than the spindle hole of the last and having an end portion shaped to seat within the outer end of the spindle hole while permitting the last to tip relatively to the spindle during its movement into the shoe.
60. In a machine of the class described, the combination with means for supporting a shoe, of means for forcing a last into the shoe comprising a member having a substantially semi-spherical portion of greater diameter than the spindle hole of the last and arranged to engage the last at the outer end of said spindle hole to force the last into the shoe while permitting the last to tip relatively to said member during its movement into the shoe.
65. In a machine of the class described, the combination with means for supporting a shoe, of means for forcing a last into the shoe comprising a rod mounted at one side of the shoe for rectilinear movement lengthwise in substantially perpendicular relation to the plane of said support, and last engaging means carried by said rod.
70. In a machine of the class described, the combination with a support for the bottom of a shoe, of means for forcing a last into the shoe comprising a rod mounted at one side of the shoe for rectilinear movement lengthwise in substantially perpendicular relation to the plane of said support, and last engaging means carried by said rod.
75. In a machine of the class described, the combination with a support for the bottom of a shoe, of means for forcing a last into the shoe comprising an operating member mounted for substantially rectilinear movement transversely of the plane of said support, and last engaging means carried by said member and movable relatively thereto in directions lengthwise of the shoe.
80. In a machine of the class described, the combination with a support for the bottom of a shoe, of means for forcing a last into the shoe comprising an operating member mounted for substantially rectilinear movement transversely of the plane of said support, and last engaging means carried by said member and movable relatively thereto in directions lengthwise of the shoe.
85. In a machine of the class described, the combination with a support for the bottom of a shoe, of means for forcing a last into the shoe comprising a rod movable lengthwise in transverse relation to the plane of said support, and last engaging means swiveled on said rod for movement relatively to the rod in response to change of position of the last during its movement into the shoe.
90. In a machine of the class described, the combination with a support for the bottom of a shoe, of means for forcing a last into the shoe comprising a rod movable lengthwise in transverse relation to the plane of said support, and last engaging means swiveled on said rod for movement relatively to the rod in response to change of position of the last during its movement into the shoe.
95. In a machine of the class described, the combination with a support for the bottom of a shoe, of means for forcing a last into the shoe comprising a rod movable lengthwise in transverse relation to the plane of said support, and last engaging means swiveled on said rod for movement relatively to the rod in response to change of position of the last during its movement into the shoe.
100. In a machine of the class described, the combination with a support for the bottom of a shoe, of means for forcing a last into the shoe comprising a rod movable lengthwise in transverse relation to the plane of said support, and last engaging means swiveled on said rod for movement relatively to the rod in response to change of position of the last during its movement into the shoe.
105. In a machine of the class described, the combination with a support for the bottom of a shoe, of means for forcing a last into the shoe comprising a rod movable lengthwise in transverse relation to the plane of said support, and last engaging means swiveled on said rod for movement relatively to the rod in response to change of position of the last during its movement into the shoe.
110. In a machine of the class described, the combination with a support for the bottom of a shoe, of means for forcing a last into the shoe comprising a rod movable lengthwise in transverse relation to the plane of said support, and last engaging means swiveled on said rod for movement relatively to the rod in response to change of position of the last during its movement into the shoe.
115. In a machine of the class described, the combination with a support for the bottom of a shoe, of means for forcing a last into the shoe comprising a rod movable lengthwise in transverse relation to the plane of said support, and last engaging means swiveled on said rod for movement relatively to the rod in response to change of position of the last during its movement into the shoe.
120. In a machine of the class described, the combination with a support for the bottom of a shoe, of means for forcing a last into the shoe comprising a rod movable lengthwise in transverse relation to the plane of said support, and last engaging means swiveled on said rod for movement relatively to the rod in response to change of position of the last during its movement into the shoe.
125. In a machine of the class described, the combination with a support for the bottom of a shoe, of means for forcing a last into the shoe comprising a rod movable lengthwise in transverse relation to the plane of said support, and last engaging means swiveled on said rod for movement relatively to the rod in response to change of position of the last during its movement into the shoe.
130. In a machine of the class described,

- the combination with a support for the bottom of a shoe, of means for forcing a last into the shoe comprising a rod mounted at one side of the shoe for movement lengthwise in substantially perpendicular relation to the plane of said support, an arm swiveled on said rod, and means carried by said arm for engaging the last to force it into the shoe.
33. In a machine of the class described, the combination with a support for the bottom of a shoe, of means for forcing a last into the shoe comprising a rod mounted at one side of the shoe for movement lengthwise in substantially perpendicular relation to the plane of said support, an arm swiveled on said rod, and a spindle adjustably mounted on said arm for engagement with the top of the last.
34. In a machine of the class described, the combination with a support for the bottom of a shoe, of means for forcing a last into the shoe comprising a rod mounted at one side of the shoe for movement lengthwise in substantially perpendicular relation to the plane of said support, an arm swiveled on said rod, and extending over the top of the shoe, and a spindle carried by said arm and having a substantially semi-spherical end portion of greater diameter than the spindle hole of the last for engaging the last at the outer end of said spindle hole, said arm being swiveled on the rod to permit the spindle to move with the last in directions lengthwise of the shoe.
35. In a machine of the class described, the combination with a support for the bottom of a shoe, of means for forcing a last into the shoe comprising an operating member mounted for movement transversely of the plane of said support and carrying means for engaging the last, said last engaging means being movable relatively to said operating member in directions lengthwise of the shoe and constructed for positioning engagement with the last at the outer end of the spindle hole while permitting the last to tip relatively thereto during its movement into the shoe.
36. A machine of the class described having, in combination, shoe engaging means, last engaging means, mechanism for effecting relative movement of said shoe engaging means and last engaging means to cause a last to be forced into a shoe, additional means constructed to project within the shoe between the shoe and the heel end face of the last to serve as a guide during said relative movement of the last and the shoe, and mechanism connected to said guiding means to permit said means to be withdrawn manually from the shoe.
37. A machine of the class described having, in combination, means for forcing a last into a shoe, means for supporting the shoe against the pressure of the last, a shoe horn arranged to guide the heel end portion of the last as the last is forced into the shoe, and means for withdrawing said horn from the shoe after the last has been forced into the shoe.
38. In a machine of the class described, the combination with last engaging means and mechanism for operating said last engaging means to force a last into a shoe, of a shoe horn arranged to guide the heel end portion of the last as the last is forced into the shoe, and operating means connected to said shoe horn to enable the operator to withdraw the horn wholly or partially from the shoe at any stage in the operation of forcing the last into the shoe.
39. In a machine of the class described, the combination with a shoe support, of means for forcing a last into a shoe on said support, a shoe horn for guiding the heel end portion of the last in its movement into the shoe, a pivoted support for said horn movable to withdraw the horn from the shoe, a flexible connection between said horn and support, and manual means for operating said support to withdraw the horn from the shoe.
40. A machine of the class described having, in combination, a shoe support, means for forcing a last into a shoe on said support, a shoe horn for guiding the heel end portion of the last in its movement into the shoe, and means for engaging the exterior surface of the shoe frictionally and drawing the shoe into final position on the last.
41. A machine of the class described having, in combination, a shoe support, means for forcing a last into a shoe on said support, a shoe horn for guiding the heel end portion of the last in its movement into the shoe, a band for embracing the heel end portion of the shoe, and means for operating said band to work the shoe into final position on the last.
42. In a machine of the class described, the combination with means for forcing a last into a shoe, of a shoe horn for guiding the heel end portion of the last in its movement into the shoe, means for frictionally engaging the exterior surface of the upper of the shoe and working the shoe over the last, and mechanism for enabling the operator to manipulate said shoe horn and upper engaging means at will to withdraw the horn wholly or partially from the shoe and to work the upper of the shoe over the last.
43. In a machine of the class described, the combination with means for engaging a last partially inserted in a shoe, of a shoe horn arranged to project within the shoe between the shoe and the heel end face of the last, means for engaging the exterior surface of the upper of the shoe at the heel end portion, and independently operative

connections to said horn and upper engaging means for moving the horn in a direction to withdraw it from the shoe and for operating the upper engaging means to draw the shoe over the last.

44. A relasting machine having, in combination, a spindle operable to force a last into a shoe, a band movable into position

to embrace the rear portion of the shoe, and means to close said band about the heel portion of the shoe and to move it toward the top of the last to work the rear portion of the shoe over the last. 10

In testimony whereof I have signed my name to this specification.

ADELORD BOURGEOIS.
